UNITED STATES PATENT OFFICE.

SAMUEL B. LAVICK, OF CHICAGO, ILLINOIS.

DESIGN FOR A DISPLAY CABINET FOR BELTS AND BELT BUCKLES.

Application filed August 19, 1922. Serial No. 3,459. Term of patent 3½ years.

To all whom it may concern:

Be it known that I, SAMUEL B. LAVICK, a citizen of the United States, residing at Chicago, in the county of Cook and State of Illinois, have invented a new, original, and ornamental Design for Display Cabinet for Belts and Belt Buckles, of which the following is a specification, reference being had to the accompanying drawing, forming part thereof.

The drawing is a perspective view of my new design for display cabinet for belts and belt buckles.

I claim:

The ornamental design for a display cabinet for belts and belt buckles, as shown.
Chicago, Ill., Aug. 1, 1922.

SAMUEL B. LAVICK.
